Kingsley, Clark

Attorney.

UNITED STATES PATENT OFFICE

CHARLES F. OSGOOD, OF CLAREMONT, NEW HAMPSHIRE, ASSIGNOR TO SULLIVAN MACHINERY COMPANY, A CORPORATION OF MASSACHUSETTS

DRILLING MECHANISM

Application filed March 13, 1924. Serial No. 699,122.

This invention relates to drilling mechanism.

An object of my invention is to provide an improved drilling mechanism. Another object is to provide an improved drilling mechanism in which is embodied a feeding mechanism, a tool rotation mechanism, automatic means for controlling the feeding mechanism which is responsive to variations in the resistance to rotation of a tool, and a hammer piston. A further object of the invention is to provide an improved means for controlling the same. Another object of my invention is to provide an improved manual controlling means comprising a plurality of valves, one of which is adapted to control the actuation of the feeding mechanism and the tool rotation mechanism independently of the operation of the hammer piston, a further object being to provide an improved valve mechanism for controlling the feeding and rotation mechanisms so that the same may be substantially instantly operated as is often necessary.

In the accompanying drawings I have shown for purposes of illustration one form which my invention may assume in practice.

In these drawings,—

Fig. 1 is a side elevation of my device partly broken away to show details of construction.

Fig. 2 is an enlarged longitudinal transverse fragmentary section taken on line 2—2 of Fig. 1.

Fig. 3 is a horizontal transverse section on line 3—3 of Fig. 1.

Fig. 4 is a detail sectional view of the manual controlling valves.

In the illustrative form of my invention I have shown the same embodied in a stoper type of drill which comprises the usual motor cylinder 1 having at its upper end a steel receiving chuck 2 rotatably mounted in a chuck housing 3 carried on the forward end of the cylinder, the steel 4 and chuck 2 being rotated as by a gear 5 mounted upon a rotatable shaft 6, the lower end of which carries one of two intermeshing rotation motor rotors 7 adapted to be actuated by a suitable source of fluid supply controlled by a main

control valve 8 rotatably mounted in the head 9 carried on the lower end of the motor cylinder 1. Projecting downwardly from the head 9 and positioned coaxially with the axis of the motor 1 is a feed cylinder 10 within which is slidably mounted a piston and piston rod 11 and 12 respectively, the latter having non-rotatable engagement with the cylinder 10 as by a key 13 and terminating in a two point swiveled foot piece 14. The key 13 is desirable in view of the fact that part of my mechanism to be described is controlled by resistance to rotation of the tool.

The particular means for controlling the feed so that the control thereof will be responsive to variations in the resistance to steel rotation comprises a valve 15 disposed, herein shown as transversely, but which could be in any direction desired, in a bore 16 formed in the head 9, the outer ends of which terminate in enlarged bores 17 and 18 respectively closed by plugs 19 and 20. More specifically, the valve 15 has an annular groove 21 formed in the periphery of the main cylindrical portion thereof and from which a stem 22 projects to carry a conical shaped valve member 23 which has flat portions 24 thereon to allow a certain amount of fluid to flow as will be hereafter described. The opposite end of the valve 15 carries an enlarged piston 25 reciprocably mounted within the bore 18 and said valve is held in substantially balanced condition as by a spring 26 surrounding a stem 27 projecting outwardly from the piston 25. The valve structure so far described is capable of co-operation with suitable passage means to decrease or shut down the flow of actuating fluid to the feed cylinder and to increase the flow of fluid to the rotation motor as the resistance to rotation of the tool 4 increases. To accomplish this function a passage 28 communicates with the main control valve 8 and terminates in the supply chamber 17. A passage 29 communicates with said supply chamber and the feed cylinder as by the annular groove 21 in the valve 15, the latter being in the position shown in Fig. 2, and the valve 15 is now capable of allowing the feeding of the tool. At the same time fluid will flow

from the chamber 17 past the flattened portions 24 and through passage 30 to the inlet chamber 31 of the rotation rotors 7. Communicating with the chamber 31 is a passage 32 leading to the chamber 18 on the outer side of the piston 25. The fluid for actuating the hammer piston may be controlled by any suitable port means in the main control valve 8, but in order to control the feed and rotation independently thereof, I have provided a valve 33 longitudinally movably and centrally disposed in the main control valve 8 which is adapted to control flow of fluid through a port 34 and annular groove 35 which in turn controls the flow of fluid through passage 28 leading to the constant fluid supply chamber 17. The central valve 33 is actuated by a trigger lever 36 pivotally mounted upon the main or throttle lever 37. Rotation of the main control valve 8 can permanently disconnect the annular groove 35 and the passage 28 for completely shutting down the drill. If, however, it is desired to shut off only the feed and rotation mechanisms, the trigger controlled lever 36 may be instantly actuated.

In the operation, assuming the motor hammer piston to be running and with pressure fluid flowing through passages 29 and 30, respectively, to the feed and rotation mechanisms causing the same to be actuated, as resistance to rotation of the tool 4 varies, such for instance that it should increase above normal, caused by being caught in a seam, or other reasons, the rate of rotation of rotors 7 will decrease which will reduce the amount of air consumed, thereby with a resultant increase of pressure in the chamber 31. During normal operation, fluid to the feed cylinder would flow through passage 29 and annular groove 21 thereto, but when pressure flowing from the passage 30 is built up in chamber 31 as mentioned, the same is transmitted through passage 32 to chamber 18 to cause movement of valve 15 in a left hand direction thereby partially restricting or shutting off the passage 29 and cutting down or preventing further flow of actuating fluid to the feeding mechanism. However, on said movement, the conical valve portion 23 will be moved away from its seat and with the aid of the flattened portions 24 more air will be allowed to flow through the passage 30 to the rotation motor, thereby causing greater rotative force to be exerted upon the tool 4. Upon a decrease of resistance to rotation, pressure for actuating the rotation rotors 7 will be decreased with a resultant decrease of pressure in the chamber 18 and moving of the valve 15 to its right hand position until the pressure within the chamber 17, acting upon the outer end of the valve 15 is equal to the pressure in the chamber 18 plus the pressure of the spring 26. It will herein also be noted that when the supply of pressure fluid to the

feeding means is cut off by the valve 15, the drill will not be fed an appreciable distance by the expansive action of the fluid as the inherent leakage between the feeding parts in a rock drill is sufficient to decrease the feeding pressure so that such feeding movement, after the supply has been cut off, is very slight.

Thus by my improved construction substantially no air is wasted in controlling the feed for I decrease or shut the supply off and the feed cylinder is vented to atmosphere only when desired as by a usual bleed port in the valve 8. Also by my improved construction I not only have automatic control of the feeding but also an instantly operable manual control so inter-related with respect to the automatic means that instant control can be had of only the most vital elements such as the rotation and feeding.

While I have in this application specifically described one form which my invention may assume in practice, it will be understood that this form of the same is shown for purposes of illustration and that the invention may be modified and embodied in various other forms without departing from its spirit or the scope of the appended claim.

What I claim as new and desire to secure by Letters Patent is:

The combination in a drilling mechanism comprising a tool, rotation means therefor actuated by fluid pressure, fluid actuated feeding means for said tool, and means responsive to the resistance to rotation of said tool for automatically shutting down the flow of fluid to said feed and increasing the flow to said rotation means.

In testimony whereof I affix my signature.

CHARLES F. OSGOOD.
